(57) **CLAIM**

The ornamental design for a portable power station, as shown and described.

DESCRIPTION

FIG. 1 is a perspective view of a portable power station showing our new design;

FIG. 2 is another perspective view of the portable power station showing our new design;

FIG. 3 is a front elevational of the portable power station seen in FIG. 1;

FIG. 4 is a rear elevational view of the portable power station seen in FIG. 1;

FIG. 5 is a right side elevational view of the portable power station seen in FIG. 1;

FIG. 6 is a left side elevational view of the portable power station seen in FIG. 1;

FIG. 7 is a top plan view of the portable power station seen in FIG. 1; and,

FIG. 8 is a bottom plan view of the portable power station seen in FIG. 1.

In the drawings, the broken lines depict portions of the portable power station that form no part of the claimed design. Shade lines having a combination of long and short lines, show contour and not surface ornamentation.
